UNITED STATES PATENT OFFICE.

WILFRED H. HARRIS, OF PORTLAND, OREGON, ASSIGNOR OF ONE-FIFTH TO ARTHUR C. HARRIS, ONE-FIFTH TO PERCIVAL E. HARRIS, ONE-FIFTH TO REGINALD E. HARRIS, AND ONE-FIFTH TO ERNEST F. HARRIS, ALL OF PORTLAND, OREGON.

COMBINED CUPBOARD AND FOLDING TABLE.

Application filed December 23, 1920. Serial No. 432,745.

To all whom it may concern:

Be it known that I, WILFRED H. HARRIS, a citizen of the United States, and a resident of Portland, county of Multnomah, and 5 State of Oregon, have invented a new and useful Combined Cupboard and Folding Table, of which the following is a specification.

This invention relates to improvements in 10 combined cupboard and folding table of the class adapted to be carried on the running board of an automobile, and an object of the present invention is to provide a cupboard of ample size to store lunch dishes, cooking 15 utensils, and necessary supplies for camping parties, provision being made for holding folding camp stools.

Another object is to provide a frame that 20 can be permanently attached to the running board of a motor car and be adapted to receive the cupboard and folded table, a cover being provided to fit over and exclude dust therefrom.

Another object is to provide a cupboard of 25 simple construction, with a folding table that will be rigid when set up, and that can be quickly folded or set up as required.

Another object is to make a cupboard and 30 folding table that will be dust proof when folded and latched.

Other objects will appear to those skilled in the art as the description proceeds, reference being had to the accompanying drawing in which—

35 Figure 1 is a side elevation of a motor car showing the application of the invention;

Figure 2 is an end view of the holding frame and cover with a part broken away to show details of attaching to running 40 board;

Figure 3 is a plan of a portion of a running board with the holding frame attached thereto;

Figure 4 is a side elevation of the cover;

45 Figure 5 is an end elevation showing a table top raised but with the hinged supports folded into the cupboard;

Figure 6 is a side view in the folded position and showing latches;

50 Figure 7 is a sectional view taken on line 7—7 of Figure 5;

Figure 8 is a plan of the table set up with a part broken away to show one of the supports and

Figure 9 is a side elevation of the table 55 set up.

The numeral (1) indicates an automobile provided with the usual running board (2). Attached to the running board is the frame (3) by means of the bolts (4) to (7) inclusive, cleats (8) and (9) are preferably used to prevent damage to the running board which might be caused by the bolt heads or nuts. The frame (3) may be located as shown, or it may be attached further forward which ever is the most convenient. A cover (10) is provided to fit over the frame (3) and is held by any suitable fastener as for instance the hasp and hook (11) and (12) and staples (13) to (16) inclusive. 70

Suitable corners (17) are provided for strength and finish. The cupboard comprises the base board (18), the side boards (19) and (20), and the top board (21). Fixed to the side boards (19) and (20) is the 75 shelf (22), other shelves or receptacles may be added as required. Hinged to the top board (21) are the table tops by means of the hinges (25) to (28) inclusive.

When the table tops (23) and (24) are 80 raised their surface is flush with the surface of the top board (21) and thus forms the table top complete. Means for supporting the table tops (23) and (24) are provided in the swinging frames (29) to (32) inclusive 85 which are pivoted in the base (18) and top board (21) by means of dowel pins (33). The swinging frames consist of a rectangular frame comprising the pivot post (34), the supporting leg (35), the upper cross 90 piece (36), and the lower cross piece (37). Blocks (38) of a thickness to equal the thickness of the base board (18) are used when the table is set up to support the legs (35). Suitable fasteners are provided to hold the 95 table tops (23) and (24) in the closed position and consist of the hooks (39) pivoted at (40), and adapted to hook over pins (41) on the table tops.

In operation the cover (10) is removed 100 and the cupboard lifted out by means of the handles (42), the hooks released from the pins (41), the table tops (23) and (24) raised, and held by swinging the frames (30) to (32) out under said tops, and after 105 placing the blocks (38) under the legs (35) the table is ready for use.

The means above described cover the ob-

jects of my invention but I am aware that modifications may be made in the construction thereof within the scope of my invention.

5. I claim:

A combined cupboard and folding table comprising a rectangular cupboard frame having a plurality of cross-members therein for the support of various utensils, a front 10 and a rear cover hingedly connected to the top member of the frame adapted to close the cupboard and to be swung into a horizontal position so as to be flush with the top member and to form a table, two supporting frames pivotally supported adjacent the 15

sides of the cupboard between its top and bottom members for the front and the rear cover adapted to disappear in the cupboard when the covers are closed and to be swung outwardly horizontally so as to rest on the 20 ground surface and to support the end portions of front and rear covers when the latter are swung into their horizontal position, two hooks pivotally secured to each side of the cupboard and corresponding pins on the 25 covers in operative relation thereto adapted to be engaged by the same so as to firmly bind the covers to the cupboard.

WILFRED H. HARRIS.
